UNITED STATES PATENT OFFICE

2,645,680

PULSE DISTRIBUTOR, INCLUDING ELECTRIC DISCHARGE DEVICES

Alec Harley Reeves, London, England, assignor to International Standard Electric Corporation, New York, N. Y., a corporation of Delaware

Application October 3, 1947, Serial No. 777,818
In Great Britain October 3, 1946

8 Claims. (Cl. 179—15)

1

This invention relates to pulse distributors of the type which distribute individual pulses in a pulse train between a number of individual circuits.

The object of the invention is to apply novel means to this purpose.

According to one of its aspects the invention consists of a pulse distributor comprising a plurality of gaseous electric discharge gaps adapted to fire in succession in a predetermined order in response to incoming pulses of electrical energy applied in common to the said gaps and individual circuit being connected to each gap for the transmission of an outgoing pulse when the associated gap fires in response to an incoming pulse.

According to another of its aspects the invention consists of a pulse distributor comprising a cold cathode gaseous discharge tube having a plurality of gaps adapted to fire in succession in a predetermined order in response to incoming pulses of electrical energy applied in common to the said gaps, an individual circuit being connected to each gap for the transmission of an outgoing pulse each time the associated gap fires in response to an incoming pulse.

Certain embodiments of the invention will now be described in relation to the accompanying drawings in which:

Fig. 1 is a circuit diagram of a simple form of distributor, using a multi-gap gaseous discharge tube, suitable for distributing the individual pulses of a train of pulses amongst a number of individual circuits.

Fig. 2 is a circuit diagram of a more elaborate form of distributor performing function analogous to those of the distributor illustrated in Fig. 1.

Fig. 3 is a circuit diagram of a distributor suitable for generating a repeated pulse train, each pulse of a train being under the control of an individual circuit.

These three embodiments make use of gaseous discharge tubes of the type having a number of gaps adapted to fire in succession in response to pulses of electrical energy applied to the said gaps in common due to the influence of a discharging gap on the potential required to fire an adjoining unfired gap, at least one electrode of each gap being separately led out of the tube, so that an individual circuit can be associated with each gap though the said pulses are applied to all in common.

Tubes of this type are described in specification No. 763,655 filed July 25, 1947 of A. H. Reeves 25

2

for "Gaseous Discharge Tubes" and a brief description thereof will now be given.

In this specification there is described cold cathode gaseous discharge tubes having a number of discharge gaps which fire in succession in a predetermined order, on application of pulses to the said gaps in common, due to ionisation of an unfired gap caused by the discharge in an adjoining fired gap.

10 A first pulse applied to the tube will fire only a predetermined gap called the starting gap and various alternative measures to ensure this include the closer spacing of the electrodes of the starting gap in comparison with the other gaps, a bias potential applied to the starting gap only, or the provision of a permanently discharging gap, called a pilot gap, adjoining the starting gap, causing this gap to be permanently ionised.

15 After a sequence of discharges of the gaps of the tube, and when the last gap (in the predetermined order) has fired, all discharges are extinguished and the tube is allowed to deionise before the commencement of another firing cycle.

20 If it is required to operate such a tube from a continuous sequence of regularly spaced pulses, a limit is set to the permissible frequency of pulse repetition by the need for a time interval between pulses, long enough to allow the gaps to become deionised (except the starting gap when a pilot gap is provided as previously described).

25 If gaps (except aforesaid) remained ionised, there would be no guarantee that the starting gap would fire first, in preference to the others, in a second or subsequent cycle of pulses nor that the predetermined firing order would be maintained.

30 To enable higher pulse rates to be used, measures to reduce deionising time may be taken and this may be done by the use of special gas atmospheres in the tube.

35 Alternatively it may be arranged to ensure that one or more pulses succeeding that which fires the last gap, are prevented from firing any gaps in the tube so that a time longer than the interpulse interval is allowed for deionisation of the gas in the gaps.

40 Methods of doing this are described in U. S. Patent No. 2,516,915 issued August 1, 1950 of A. H. Reeves 29 for "Gaseous Discharge Device" where (inter alia) the reduction of the inter-

45 electrode voltage, so that pulses do not reach the level necessary to cause firing, for the duration of such one or more pulses, or the use of two or more tubes operating alternatively, are outlined.

50 55 It is possible to apply a constant inter-elec-

trode potential to the gaps of the tube, insufficient by itself to initiate a discharge in the gaps but sufficient to maintain a discharged one initiated. With such a potential applied, gaps once fired will continue to discharge and at the end of a cycle, all will be discharging and must be extinguished before the next operation cycle of the tube. There are various ways of doing this, one of which is used in the embodiments of the invention to be described.

If no such discharge-maintaining potential is applied, discharges will collapse between pulses, during the firing cycle of the tube and the interval between pulses must not be so long that the ionisation can fall below the level necessary to secure sequential firing.

This involves the use of pulse rates such that the tube has not time to become deionised between consecutive pulses at the end of the firing cycle after extinguishment of the discharges, and measures such as those described in said U. S. Patent No. 2,516,915 become essential.

A phenomenon occurring in multi-gap tubes of this type, is called the "Memory effect."

This effect consists of a rise in the voltage required to fire a gap, which follows an extinguished discharge in that gap, when certain electrode materials and gasses are used in the construction thereof.

If tubes possessing this feature, are supplied with pulses to their gaps, in common, and with no constant discharge-maintaining potential, a gap once fired, will ionise the adjacent unfired gap and extinguish at the end of the pulse which fired it. The next pulse will fire the ionised adjacent unfired gap but will not refire the extinguished gap owing to the said rise in its critical firing voltage, it being arranged that the pulse amplitude is below such critical voltage.

This "memory effect" persists long enough to ensure that gaps once fired, will not again fire during the firing cycle of the tube, but when all gaps have fired and all possess the "memory effect" the first gap to recover will be that which has been extinguished for the longest time, i. e. the starting gap, and this alone will fire on the first pulse of the next cycle. A corresponding decay of the memory effect will pass down the gaps of the tube in the predetermined firing order, in advance of the firing sequence so that all in turn are ready to fire from successive pulses.

A small bias may be applied to the starting gap to make quite sure that the sequence starts with that gap in cycles after the first but this bias must not be large enough to leave the starting gap permanently discharging. It is also an advantage to insert a relatively large resistance load in series with one of the common pulse feed connections to the gaps so that immediately on the firing of one gap, the increased voltage drop in the resistance makes it impossible for another gap to fire from the same pulse.

This enables the tube to be worked at a lower level of discrimination due to memory effect between gaps and still secure the correct firing order.

In Fig. 1 a gaseous discharge tube 1 has a common anode 2 consisting of a straight bar or strip and a series of individual cathodes in the form of rods or strips at right angles to the anode and spaced therefrom at one end of each cathode, so as to define discharge gaps, the tube illustrated having ten cathodes and ten gaps 3, 4, 5, 6, 7, 8, 9, 10, 11 and 12.

Anode 2 is connected through an impedance

13 to the positive pole of a battery 14 which may be regarded as representing any convenient source of direct current supply.

5 The various cathodes are separately led out of the tube and each is externally connected through an individual resistance and transformer in series to a common connection leading to the negative pole of battery 14. Only one such resistance and transformer 15 and 18 respectively are shown in the drawing terminal 19 being connected to the secondary winding of the transformer. All cathodes are connected to similar individual circuits.

15 The potential applied to the gaps of the tubes by battery 14 is such that it cannot by itself initiate a discharge in any of the gaps but is sufficient to maintain a discharge, once initiated.

Positive pulses are applied to the anode of the tube through feed condenser 16 from a common "busbar" 17.

20 The pulses from 17 consist of repeated trains of consecutive pulses and the gaps fire in turn from successive pulses until all are fired.

A gap once fired, continues to discharge till all have fired, due to battery 14.

25 When all gaps have fired, they must be extinguished and allowed to deionise before the next firing cycle can commence.

30 There are various ways of extinguishing the discharges but it is proposed in this and the other embodiments to be described, to provide a pulse (hereinafter called the "quenching pulse"), of the opposite polarity to that of the pulses (hereinafter called the "firing pulses"), which fire the 35 gaps.

These quenching pulses will oppose battery 14 and reduce the inter-electrode potential to that which produces the required speed of deionisation.

40 Where the pulse rate is such that the interpulse interval is too short to permit the deionisation of the tube between consecutive pulses the quenching pulse must be prolonged beyond the normal interval between firing pulses.

45 Each time a gap fires, its transformer 18 will give an output and the nature of this output will depend upon the wave form of the current in the associated gap and the frequency characteristic of the transformers. Since the various gaps remain discharging for different lengths of time according to their positions in the tube there will be some variation in the output as between the different transformers and where this is important, a differentiating network may be introduced so that only the inception of the discharge is recorded.

50 It is contemplated that the individual pulses from the busbar, may carry modulation of some kind, and it has been found that, with pulse rates such that a gap fires at rates up to about 1000 times per second, and its corresponding firing pulse is modulated at some frequency, a low frequency transformer will give an output consisting substantially of such modulating frequency, the 55 pulses component being lost in the transformer, and this irrespective of the different discharge duration of the different cathodes.

For higher frequencies it is preferable to use more specific de-modulating means, and a low pass filter connected to terminal 19, may serve the purpose.

Fig. 2 shows a more elaborate arrangement having the same basic function as that of Fig. 1 but capable of responding to higher pulse rates.

55 A similar tube to that illustrated in Fig. 1 is

used and corresponding items of the tube and its associated circuits are given the same reference numerals in both figures.

The cathodes of the tube have separate individual circuits as before, though here two of them are shown (those of the first and last cathodes) and one consists of resistance 15 and transformer 20, the other having a similar resistance and transformer 21 and 22 respectively.

The secondary windings of these transformers are connected to individual gate devices of which two are shown, 23 and 24 all being identical.

The function of these gate devices are to open a gate to permit the passage of one pulse in each cycle of a continuous pulse sequence, and to demodulate that pulse, where it is modulated, give an output at the modulating frequency.

The associated gap of the tube provides the gating impulse.

The discharges in the tube are controlled by pulses from a master pulse generator 45 which is synchronized with the pulses from the busbar 46 and, in certain circumstances, both may be derived from a common source, though it is only necessary to have a distinctive feature in one pulse of the pulse trains from the busbar (such as the quenching pulse on 17 in Fig. 1 for instance) to enable a separate pulse generator 45 to be kept in step with the pulses from the busbar. The tube is again extinguished between firing cycles, by a quenching pulse.

Each of the gate devices receives all the pulses from the busbar but each is only active when rendered so by the discharge of its associated gap.

The method of operation is as follows:

The tube cathode circuit transformers pass a positive pulse at the moment of firing of their associated gaps, and all simultaneously pass a negative pulse on the quenching of the tube. This negative pulse is ignored by the gate devices as they incorporate a rectifier and in any event, there will probably be no pulse from the busbar at these moments and the devices need pulses from both sources to actuate them.

Each gate device has a condenser 25 and a resistance 26 which improve the pulse shape delivered by the associated cathode transformer and also decouple the transformer circuit from the busbar.

The busbar is also connected to each gate device through an individual condenser 34 and resistance 35 which are generally chosen so as not to alter the wave form of the busbar pulses.

Outlets to gate devices associated with intermediate gaps of the tube are indicated by the arrows 37, 38, 39, 40, 41, 42, 43 and 44, these gate devices and the details of the cathode circuits of the associated tube gaps being omitted to simplify the drawing.

In each gate device there is a closed circuit consisting of a rectifier 27, the primary winding of a low frequency transformer 30, a battery 31, and a resistance 28. The transformer winding and battery are bridged by a condenser 29.

Resistance 26 from the tube cathode, and resistance 35 from the busbar are both connected to the said closed circuit at the junction of 27 and 28.

In a working circuit, of course there will be a common point, probably earthed to which will be connected the negative side of master pulse generator 45, the negative pole of battery 14 in the tube circuit, and the junction of 28, 29 and 31 in the gate device and a second conductor of the busbar. These connections need not provide

a continuous conducting path and may be made through condensers for instance. It is possible to separate the gate and busbar circuits from the tube circuits by using separate "earths" for each by taking two leads from the secondary windings of the cathode transformers (20-22 etc.) instead of "earthing" one side of these secondaries.

Rectifier 27 is normally biased to cut off by battery 31. Pulses from the busbar are of positive polarity tending to open the rectifier but being of insufficient amplitude to do so by themselves. When the associated gap fires the pulse from 26, added from the pulse from 35 is sufficient to "open" the rectifier 27.

It is arranged that the pulse from a cathode slightly leads the corresponding pulse from the busbar and only on the inception of the latter, is the rectifier opened. The pulse overlap is arranged to terminate with the end of the tube pulse.

The busbar pulse may be modulated in time or duration, but the tube pulse has constant timing, so that the period during which the rectifier is open commences at the varying time of the busbar pulse and ends with the constant trailing edge of the tube pulse, so that a pulse flows in the closed circuit modulated in duration in conformity with time of duration modulation carried by the busbar pulse. The high frequency components are bypassed by condenser 29 so that

the reactance of transformer 30 and battery 31 does not interfere with the opening and closing of the rectifier in response to pulses from tube and busbar.

The low frequency component will effect transformer 30 which will have in its secondary winding a wave form corresponding substantially to the fundamental and lower harmonics of the pulse repetition frequency of the pulses in the closed circuit. Time or duration modulation of the busbar pulses, in either case appears as duration modulation of the pulses in the closed circuit. This modulation can be regarded as a variation in the "on-off" ratio of these pulses and it is well known that a variation of this ratio varies the amplitude of the fundamental component of the pulse waveform.

The transformer used is preferably one with a frequency characteristic such that it attenuates the harmonies more than this fundamental, and the addition of a low pass filter 32, between the secondary winding of 30 and terminals 36, produces an output at terminals 36 containing substantially the modulating frequency only.

Amplitude modulation of the busbar pulses would have a similar effect.

The embodiment illustrated in Fig. 3 is very similar to that in Fig. 2 corresponding components are given the same reference numerals in the two figures.

The differences consist of the addition of a transformer 47 in series in the gate device, closed circuit and the substitution in place of the connection through 34 and 35 from the busbar of a connection through condenser 49 and resistance 48, from a saw tooth pulse shaper 50 which modifies the pulses of the master pulse generator 45, to saw tooth waveform. The busbar is connected to the secondary of transformer 47.

A modulating frequency is applied to terminals 36 instead of being taken therefrom.

Three potentials are simultaneously applied to the rectifier 27, first pulses from the associated cathode of tube 1, secondly the saw tooth pulses from 50 and thirdly the instantaneous amplitude of the modulating wave from terminals 36. At a

certain point in the potential rise of the saw tooth waveform, a potential sufficient to "open" rectifier 27, will be applied to the closed circuit, and current will flow in the circuit. It will generally be arranged that the current will always stop at a constant time coinciding with the end of the saw tooth pulse since the cathode pulse will be of longer duration in the case of earlier firing cathodes.

The time at which the rectifier opens will of course be influenced by the contribution to the total voltage across the rectifier, of the modulating wave from 36, and the leading edge of the resulting pulse in the closed circuit, will be modulated in time at the modulating frequency.

The output of 41 applied to the busbar will tend to be differentiated by the transformer 47 to produce a pulse at the beginning of the closed circuit pulse and a pulse of opposite polarity at the end of the closed circuit pulse. If it is necessary to modify this wave form either to reshape the first pulse in the busbar or to eliminate the reverse pulse following it, or both, a single pulse shaping circuit on the busbar can perform this function for all pulses, and separate pulse shaping circuits for all gate devices are unnecessary.

Taking Figs. 2 and 3 together therefore, the former provides a means of taking repeating trains of pulses from a common source (the busbar) and distributing them amongst various individual outlets (connected to terminals 36 of the various gate devices associated with various cathodes of tube 1) and at the same time demodulating them so as to extract any modulation intelligence contained in the various pulses of the trains. Fig. 3 on the other hand performs a converse function, taking various channels (connected to terminals 36 of the various gate devices) and enabling each to influence an individual pulse in pulse trains applied to the busbar.

It is envisaged that such devices may be used in a communication system enabling several physical channels to communicate with a corresponding number of physical channels, over a common connecting link (the busbar with or without intermediate apparatus) on a time division pulse multiplex basis. In specification No. 794,724 filed December 30, 1947 of D. H. Ransom-W. L. Roberts-R. H. Taplin 14-1-1 for "Pulse Time Position Switching System" a system of this nature is described wherein physical circuits are connected to scanned elements of a distributor, on the scanning element of which, the various physical channels are represented by individual pulses in a repeating pulse train. After passing through linefinder circuits and selection circuits, the common output appears again on the scanning member of a second distributor whose scanned elements are connected to individual physical channels. The devices illustrated in Figs. 2 and 3 could be used in the role of the distributors mentioned in that specification.

Tubes of the type described having the "memory effect" may be used with advantage in the embodiments described and have the advantage, since each gap of the tube extinguishes, at the end of the pulse which fires it and fires once only during a firing cycle of the tube, that pulse shaping measures and measures to suppress the end-of-pulse output are unnecessary.

It also has other advantages including increased tube life since all gaps fire only once per firing cycle of the tube, for the duration of their firing pulses only, instead of continuing to dis-

charge during the whole firing sequence of the tube.

The omission of the maintaining potential with a non-memory tube is possible but presents the difficulty that a gap fires repeatedly from each pulse subsequent to that which first fired it, during each firing cycle of the tube and measures are required to enable only the first firing to be recorded by the individual gap circuits.

The use of the expedients outlined in said U. S. Patent No. 2,516,915 where one or more pulses are prevented from affecting the tube after the completion of a firing cycle, to allow extra time for deionisation, present no complication in the embodiments described, but of course, potential channels in the pulse cycle time are wasted to the extent of the pulses prevented from affecting the tube. Actually in the arrangements described, these pulses would preferably not be generated by the master pulse generator.

There are applications where such a pause at the end of a pulse train is necessary for other reasons and where this is the case, the expedients in that specification may be used with advantage to enable any given design of tube to cope with a higher pulse rate than it could handle if it had to become deionised during the normal inter-pulse interval.

It will have been observed that, whilst the arrangement of Fig. 2 has a corresponding simple or basic equivalent in the arrangement of Fig. 1 no such equivalent has been shown for Fig. 3.

Such an equivalent may be simply devised by applying a saw tooth pulse sequence, such as that derived from 50 in Fig. 3, to the pulse feed condenser 16 in Fig. 1, in place of the pulses from the busbar.

A transformer capable of passing pulses would then be substituted for 18, with its primary winding in series with the cathode circuit and its secondary connected to the busbar through suitable decoupling components to prevent interaction amongst the transformers associated with other cathodes, similarly connected to the busbar.

Modulation could be impressed upon the pulses applied to the busbar by the use of low frequency transformers, one in series with each cathode circuit, the modulating signals being applied to the primaries of these transformers.

It should be arranged that the interelectrode potential across each gap reaches the critical value at which the gap will fire, at some time during the rising voltage of the saw tooth pulse applied to the gap, the exact instant of firing being determined by the modulating voltage in the secondary of the said low frequency transformer which according to its instantaneous value will delay or accelerate the attainment of the critical firing potential of the gap.

It is possible in certain circumstances to apply rectangular pulses to the gaps of the tube instead of saw tooth pulses and still achieve modulation of the output pulses by means such as that just described.

This arises from the fact, explained in said specification No. 763,655 that there is a time element in the firing of a gap by a given applied voltage. If the voltage is raised the time lag is shortened and vice versa if the voltage is lowered. Raising and lowering the voltage in conformity with a modulating signal thus enables the firing time lag to be varied.

This may only be done effectively when the firing time lag, which can only be varied within certain limits, is a substantial proportion of

the pulse duration and therefore at the low pulse frequencies for which these simple arrangements are most suitable, a saw tooth pulse shape is generally preferable.

What is claimed is:

1. A pulse distributor comprising an envelope, a plurality of electric gaseous discharge gaps each gap including two electrodes one of which is individual to said gap, means positioning successive gaps adjacent each other so that they are ionically coupled for causing the firing of one gap to prime the adjacent gap for firing, whereby the gaps are adapted to be fired successively, means for initially firing one of said gaps, means for applying a series of pulses to said gaps in parallel, each pulse firing a successive gap, and a separate utilization device connected in series with each gap.

2. A pulse distributor according to claim 1 wherein said gaps include a plurality of cathodes each forming said one electrode of a separate gap, and separate leads extending from each of said cathodes through said envelope.

3. A pulse distributor according to claim 2 wherein a separate output transformer is connected in series to each of said leads.

4. A pulse distributor according to claim 1 wherein each of said utilization devices includes means for applying a modulation to the pulses applied thereto.

5. A pulse distributor according to claim 4 wherein said modulating means comprises means for applying audio frequency energy for amplitude modulation of said circuit.

6. A pulse distributor according to claim 1 wherein the pulses applied to said gaps consist of a repeated train of pulses, each pulse of which has a modulation signal impressed upon it with successive pulses belonging to separate intelligence channels and separate demodulating

means arranged in the utilization device associated with separate gaps to demodulate the pulses distributed to their respective gaps.

5 7. A pulse distributor according to claim 1, further comprising a local pulse generator synchronized with the pulses applied to the gaps, and coupled to said gaps, a plurality of gate circuits each associated with a separate one of said gaps and adapted to give an output only when a pulse derived from the firing of the associated gap coincides with said local pulses.

15 8. A pulse distributor according to claim 7 further including a sawtooth pulse shaper associated with said local pulse generator and actuated thereby, means for impressing an intelligence signal on each of said gate circuits for combination with the sawtooth pulses, each of said gaps being adapted to fire when the sawtooth and intelligence signals together reach a predetermined amplitude and to cease firing at the end of each sawtooth pulse whereby variable width output pulses are produced.
